UNITED STATES PATENT OFFICE.

GEORGE A. O'CONNELL, OF WORCESTER, MASSACHUSETTS, ASSIGNOR TO JOHN E. O'CONNELL, OF WORCESTER, MASSACHUSETTS.

EXPANSIBLE LOCKING KEY.

Application filed May 19, 1925. Serial No. 31,401.

My invention relates to machine elements and more particularly to an expansible locking key adapted particularly for connecting a rotatable body to a shaft.

- 5 In accordance with the prior practice, a heavy drum is ordinarily keyed to its rotating shaft by providing both the shaft and the hub of the drum with opposed keyways and then driving a key into the keyways. 10 It is necessary that this key have a fairly close driving fit in the keyways and that it be driven in firmly to prevent relative movement between the connected parts. Hence, when it is desired to remove the drum from 15 its shaft, considerable difficulty is experienced in removing this large key from the keyway into which it has been driven.

It is accordingly the main object of my invention to overcome this difficulty and to 20 provide an expansible key which may be cheaply manufactured and quickly assembled and which may be employed to connect two rotatable bodies together and which will hold them firmly and rigidly together as 25 long as desired and yet may be quickly and easily removed to disconnect them.

With this and other objects in view, as will be apparent to one skilled in the art, my 30 invention resides in the combination of parts set forth in the specification and covered by the claims appended hereto.

Referring to the drawings in which like reference numerals indicate like parts:

Figure 1 is a section partly in elevation 35 and broken away showing the central hub of a drum connected to a shaft by means of expansible key;

Fig. 2 is a top plan view of the key; and

Fig. 3 is a perspective view cut centrally 40 on a vertical plane showing the construction of the key.

In accordance with my invention, I propose to provide a key which is made of separable parts which may be moved relative to one another to form an expansible device so arranged and constructed that the key may be easily locked in position in a keyway. One embodiment of my invention, as illustrated in the drawings, comprises wedge-shaped members having plane faces sliding in the opposed keyways and beveled faces slidably mounted in parallelism and so arranged that sliding one member on the other serves to expand the key laterally while maintaining their outer faces parallel. These parts may be held together and adjusted by screw-threaded means which are so arranged that the members may be moved relative to each other to expand the key laterally or be disassembled.

60 As shown in the drawings which illustrate one embodiment of my invention, the hub 10 of a drum may be fastened to a spindle 11 by providing them with opposed keyways 12 and 13 respectively for insertion of the 65 key shown in the drawings.

The key as a whole is made to fit the keyways with a slight amount of clearance in one direction, preferably radially of the spindle, and is provided with a fairly snug 70 fit in the other direction so that there will be no play between the bodies connected together. The device as illustrated is made up of three wedge-shaped parts, the middle one 15 having a lower plane face 16 fitting in the keyway of one of the members 11 and two beveled faces 17 and 18 sloping upwardly towards each other. Slidably mounted on the two beveled faces are the end members 19 and 20 having plane top 75 faces 21 and 22 respectively, which fit against the bottom of the keyway in the drum 10 and are maintained parallel with the bottom surface of the central member 15.

In order to connect these parts together 80 and permit moving them, one relative to another, I employ a screw-threaded member which may be arranged in various ways to move the end parts up the inclined planes of the central portion. As illustrated, I prefer 85 to employ a bolt 25 which passes through aligned openings in the various members. The other end of the bolt is preferably fastened to the wedge-shaped member 19 by heading over the end of the bolt 27 to prevent it pulling out, and if desired, relative rotation between the bolt and this member 90 may be prevented by means of the pin 28, suitably fitted into a hole bored through the key to contact with both the bolt and the outer part 19. The bolt may fit tightly 95 in the member 19, but the centrally disposed openings in the members 15 and 20 are made larger than that in 19 so that the bolt may move laterally relative to these 100 two parts as the key is expanded. The screw-threaded end of the bolt projects outwardly beyond the end of the key member 20 and has a nut 29 mounted thereon which 105 is adapted to hold the parts assembled and 110

move them relative to one another. In order that the key may be easily removed from the keyway, I preferably provide the outer end of the member 22 with a lug so arranged that it may be used for prying the key from the keyway.

The operation of this device will be obvious from the above disclosure. When it is desired to lock a drum to a shaft by means 10 of the key, the nuts 29 are loosened on the bolt and the key is slid into place in the keyway, until the head 30 is positioned close to the drum 10. Then upon tightening the nut 29, the members 19 and 20 will be moved 15 up the inclined planes of the part 15, thereby making the key wider and serving to clamp it tightly against two opposed faces of the two keyways. To remove the key, it is merely necessary to loosen the bolt 29 20 slightly and then draw the parts out by pulling on the lug 30.

It will be obvious that various changes may be made in this device within the scope of the appended claims.

25 Having thus described my invention, what I claim as new and desire to secure by Letters Patent is:—

1. An expandible key to fit in a keyway

and connect a rotatable member to a shaft comprising a central member and two end 30 members which when assembled have two outer parallel plane faces and inner parallel beveled faces so arranged as to slide one on another and expand the key laterally and a screw-threaded device connected to 35 one member and passing through the others which is arranged to draw the members together.

2. An expandible key to connect a shaft and a member mounted thereon which have 40 opposed keyways, comprising a central member having one plane face fitting in a key way and oppositely sloping beveled faces, two wedge-shaped outer members, each having a plane face fitting in a keyway and a 45 sloping face slidably mounted on one of the beveled faces of the central member, a threaded member fastened to one of the outer members and passing loosely through the other two, and a nut on the threaded member, said parts being so arranged that tightening the nut serves to expand the key laterally to bind it in the keyways.

Signed at Worcester, Massachusetts, this 14th day of May 1925.

GEORGE A. O'CONNELL.
